UNITED STATES PATENT OFFICE.

MARSENA M. HOOTON, OF CHICAGO, ILLINOIS, ASSIGNOR TO HIMSELF AND
CHARLES G. PAGE, OF SAME PLACE.

INDICATOR AND ADVERTISING APPARATUS.

SPECIFICATION forming part of Letters Patent No. 373,892, dated November 29, 1887.

Application filed July 21, 1884. Serial No. 138,334. (No model.)

To all whom it may concern:

Be it known that I, MARSENA M. HOOTON, a citizen of the United States, residing at Chicago, in the county of Cook and State of Illinois, have invented a new and useful Indicator and Means for Advertising; and I hereby declare the following to be a full, clear, and exact description thereof, reference being had to the annexed drawings, forming part of the same.

An object of this invention is to provide novel and improved means whereby a set of cards can be practically, efficiently, and economically utilized as a means in cars for successively indicating at the proper times the stations or crossings to which the car or cars is or are approaching, and also for displaying to the passengers such advertisements as may be placed upon the cards alongside the names or numbers serving to indicate the names or numbers of the street-crossings or stations along the route.

A further object is to provide a novel, simple, and efficient street-crossing or station indicator which can be conveniently fitted within a car without requiring any material alteration in the construction of the car as usually made, and which can be conveniently operated by the conductor from either end of the car, so that, no matter at which end of the car the conductor is standing, he can operate the indicator and thereby notify the passengers of the crossing or station to which the car is approaching without calling out the same and without opening the car-door, whereby the objectionable feature of conductors or other attendants indistinctly calling out crossings or stations can be dispensed with and the constant opening of the car-door in cold weather avoided, in addition to which said feature the cards are rendered available for advertising purposes, so that at such time as any one or more advertisements may have been displayed for the time agreed upon, and it is desired to replace the same by new advertisements, said card or cards can be replaced by new ones at a small expense and without removing the remaining cards or in any wise changing the construction or arrangement of the devices for manipulating the same.

A further object is to adapt said apparatus

either for service in a street or railway car, or for use as a device for displaying photographs in hotels or other public or private places—as, for instance, photographs alternating with business-cards can be successively displayed where the apparatus is to be used in public places, or the cards can be omitted where photographs alone are desirable.

To such ends my invention consists in the matters hereinafter described, and particularly pointed out in the claims.

In an apparatus embodying the principles of my invention a suitable casing or box is provided with two card-receiving compartments, which are connected together by a single card-passage arranged adjacent to the front of the box, whereat an opening is provided through the front wall of one of the said compartments, in order to expose the top or front card of a pack of cards contained within said compartment. The top or front card of a pack of cards in either of the two compartments is normally held against the inner front wall of the compartment and in line with the card-passage by means of any suitable construction of spring-follower or spring-backing arranged between the cards and the rear wall of the compartment, each compartment being provided with such an arrangement of spring-follower for the purpose aforesaid.

The box or casing is provided at its front side with two independent card-shifting slides, each arranged to reciprocate over one of the two compartments. These slides are respectively arranged at opposite sides of but both in line with the card-passage, and each slide is arranged to slide back or away from the card-passage to an extent which will permit the top card of a pack within the compartment to which the slide is allotted to lie between the inner end of the slide and the card-passage, whereby when the slide is moved toward the latter it will push the card through the card-passage and carry it into the next compartment. By such arrangement the two slides and the card-passage are in one and the same plane at the front side of the box, and in order to permit a card which is being pushed through the card-passage by either slide to overlap the follower in the next compartment a depressor movable transversely to the plane of the slides

and card-passage is arranged in front of or over each compartment at a point not far from the card-passage. The depressor in front of one card-compartment is momentarily operated from and by the slide which is being advanced over the other compartment, the action being to depress the follower until the advancing card has overlapped the same and to then retract or move outwardly out of the way of the advancing card.

Various mechanical contrivances can be devised for operating the slides, and I do not confine myself to any special means for independently operating the card-shifting slides, as such will readily suggest themselves, according to the use to which the apparatus is to be put—as, for example, means suitable for operating the slides when the apparatus is hung up in a street-car will desirably differ in arrangement from means for operating the slides when the apparatus is placed in a railway-car, and, again, entirely different means may be preferable when the box with its slides and depressors is employed as a photograph showcase or album.

In the drawings, Figure 1 is a perspective view of one of the interior corners of a street-car with my indicator and advertising device applied to one end of the car, with a cord shown passing from the apparatus through the said end portion of the car. In this figure the card-operating mechanism is inclosed by a case secured to the wall of the car. Fig. 2 is a front view of the apparatus removed from the outer casing shown in the preceding figure and made of slightly-different proportions. Fig. 3 is a side view of the same with the rod F at this side of the apparatus broken away and the coiled spring removed for convenience of illustration. Fig. 4 shows on a larger scale one of the bell-clappers and devices included in its actuating mechanism. Fig. 5 represents one of the card-shifters detached from its operating mechanism. Fig. 6 represents a central longitudinal section through the apparatus shown in Fig. 2, with the cards in pack form in one compartment and the top card in the act of passing to the adjoining compartment. Fig. 7 is a like view, but with a pack partially formed in each compartment and a card in the act of passing from one compartment to the other. Fig. 8 is a transverse section taken through either one of the card-shifters and its adjuncts. Fig. 9 is a section taken transversely through one of the depressors and through the box at one side of its central partition. Fig. 10 is a face view of the apparatus made of somewhat different proportions from that shown in Figs. 2 to 9, inclusive, and adapted for a case of the conformation shown in Fig. 1. This said Fig. 10 also illustrates means by which the card-shifters can be alternately operated or brought into action. Fig. 11 is a view similar to the preceding figure with the means for operating the shifters applied to operate the upper shifter, while in Fig. 10 said means are applied to actuate the

lower one of the two card-shifters. Fig. 12 is a side view of the same with the outer casing in vertical section, in which view the spring and supporting-rod therefor at this side of the apparatus are removed for convenience of illustration.

Referring by letter to the several figures of the drawings, in which like letters denote like parts, A indicates a box or casing, which can be made of any suitable dimensions and of wood or metal, or both, as may be deemed most desirable. The box A is provided with two compartments, B, conveniently formed by arranging within the box a transverse partition, A', situated at or about the middle of the box, as in Figs. 6, 7, and 9. Each compartment is adapted to contain a pack of cards of such size as may be found best suited for the herein-described purposes for which they are intended. An opening, A², is formed through the front of the box, opposite one of the card-holding compartments, so that the top card of a pack in such compartment shall be exposed, in which way the top or front one of two or more cards opposite this opening can be seen and such matter as may be printed thereon readily read. These card holding compartments are connected or communicate with each other through the medium of a passage, A³, formed near the front of the box and adapted to allow a card to be shifted from one compartment to the other. The simplest way of providing this passage is to leave a space between the front side of the box and the partition A'. The object of this passage is to allow one card at a time to be shifted from either compartment to the other, and being situated at the front, as shown, the passage will only admit of the transfer or shifting of such card as may be at the top or front of a pack of cards in either compartment. The cards are maintained in pack form within either compartment and a pressure constantly exerted against the pack, so as to keep the top or front card thereof in line with the passage between the two compartments, by any suitable arrangement of spring-backing or spring-backed follower, (such, for example, as may be found in a variety of card-holders,) in which way the pack will be constantly pushed toward the front of the box with a yielding pressure, and hence the top card will always be maintained in position to be shifted from one compartment to the other. It will also be seen that this spring backing or follower in a compartment accommodates itself to the size of pack, being pushed back as the pack increases in size and moving forward as the size of the pack is diminished.

In the present illustration the spring backing or follower consists of a plate, C, between which and the back of the box are arranged springs C', tending to force the plate toward the front of the box.

It will be evident that various forms of springs for spring-backing the pack can be employed, the springs herein shown, which are

common in apparatus for holding cards, serving, however, to illustrate the use of a follower in connection with the other novel features of the apparatus.

5 The card-shifters D each consist, essentially, of a slide arranged to push a card from one compartment to the other through the passage between the two compartments. For this purpose each card-shifter is normally 10 maintained in position at one end of the box and held in readiness to be moved forward or toward the middle of the box, in order to shift the top card of a pack in either compartment. These shifters or card shifting slides are each 15 formed of a plate arranged to work in a plane parallel with the front of the box, and preferably made somewhat wider than the card to be shifted.

A card-shifter is provided for each compartment, and these card shifters are guided by slots or ways A⁴, formed longitudinally through the sides of the box, near the front of the same.

Referring to Fig. 5, it will be seen that the card-shifter has at one end two corner projections, D', giving the effect of a wide notch or recess formed in the plate between its two front corners. The space between these two corner projections is substantially equal to the width of a card, so that when the card-shifter is 20 moved forward to engage and shift a card from one compartment to the other the card, being at one end engaged by the shifter between the corner projections of the latter, will, during the forward movement thereof, be steadied 25 against any side movement, and hence will be prevented from shifting sidewise into either guideway A⁴.

Each card-shifter is provided with a handle, or with some suitable appendage by which it 30 can be conveniently connected with means for operating the same, which said means can consist of cords or levers, as desired.

As herein shown, a narrow plate or cross-bar, D², arranged across the front of the box, 35 is secured to each card-shifter, one of said cross-bars being provided for each card-shifter and furnished with a knob, A⁶, or with any device with which a cord or hooks on cords can be conveniently connected. Each cross-bar D² is arranged to slide over the front of the box, and is bent back at its ends, extending 40 beyond the sides of the box, so as to bring its said ends in position to be secured by screws D³ or other suitable means to lateral wings or 45 extensions d of the plate forming the card-shifter, these said lateral or side edge extensions of the plate being extended out through the ways A⁴ at the sides of the box. This arrangement will be best understood by referring 50 to Fig. 8, illustrating the card-shifting mechanism, embracing a plate arranged to work through the slots A⁴ and a cross-bar, D², attached at its ends to the extensions d, formed 55 at the rear corners of the plate.

60 Each card-shifter, when moved forward, is moved against a yielding spring resistance,

which, the moment the shifter is released, serves to throw the same back to its normal position, in which way the card-shifters are both normally maintained in such position 70 that when moved forward therefrom the advancing shifter will engage the top card of a pack in the nearest compartment. Said spring resistance is effectively provided by means of long spring coils E, loosely arranged on stationary guide-rods F, which are supported at 75 the sides of the box.

As a means for steadyng the card-shifters, and also for providing the same with abutments or shoulders for confining the springs 80 on the rods and for acting against the ends of the springs, so as to compress the latter when either card-shifter is moved forward, each card-shifter is connected with a pair of sleeves, D⁴, arranged to slide on rods F, whereby the 85 ends of the springs on said rods shall abut against the sliding abutments or sleeves D⁴. As herein shown, the lateral wings or extensions d of the card-shifters are secured by the screws D³ to plates d', formed with or rigidly 90 secured to the sleeves D⁴, as best illustrated in Fig. 8, and the rods F, arranged parallel with the sides of the box, are secured at their ends to bracket-plates A⁵, projecting from the corners of the box, as in Figs. 2, 10, and 11. A 95 single spring-coil is preferably arranged on each rod and between each opposing pair of sleeves fitted to slide on the rod, it being seen that by thus employing a long spring-coil the same will not be compressed or compacted to 100 an objectionable extent when either card-shifter is moved forward, since in a long coil the accumulation will be more gradual and less rapid than in a short spring-coil. The coil form of spring is herein employed as occupying 105 but little space, and in other respects being more serviceable than any arrangement of bow or analogously shaped springs.

Assuming the cards to be all in pack form in one compartment, as in Fig. 6, it will be 110 seen that the front face of the front or top card of the pack will be exposed through opening A² in the front of the box. This front card will be in the same plane as that occupied by the card-shifters and the passage between the 115 two compartments, and hence if the shifter back of said card is moved forward it will engage the top card and push the same forward through passage A³ between the two compartments; but as the follower in the unoccupied 120 compartment or any card upon the said follower will be normally held against the inner side of the front of the box, and hence in the way of the card to be advanced, it becomes necessary to depress or push inwardly the follower to such extent as shall leave room between the follower or any cards thereon and the front of the box for the advancing card. To such end I provide an automatically-operated depressor, which, during the advance of 125 a card-shifter over one compartment, shall for a proper length of time push back slightly the 130

follower in the next compartment, and thereby make room in front of said follower or any card or cards thereon for the advancing card.

- Over or in front of each compartment, and 5 at points adjacent to and at opposite sides of the passage A³ between the compartments, is a depressor, G, arranged to work through a slot or opening formed transversely through the front of the box, one of said depressors 10 being provided for each compartment. These depressors normally stand out from the front of the box, so as to allow the front card of a pack in either compartment to lie against the inner side of the front of the box, so that said 15 card shall be in the plane in which the shifters and the passage between the compartments are situated. While, however, a card is being pushed forward from one compartment to the other, as in Fig. 6, the depressor in front of 20 the compartment into which said card is being pushed will be pushed inwardly, so as to depress or push inwardly the follower in said compartment to an extent which will allow the advancing card to lap over or pass in front 25 of the edge of either the said follower or card thereon nearest the passage, in which way the advancing card can wedge in between the follower or cards thereon and the front side of the box. As soon, however, as the advancing card 30 has been brought into positionlapping over the follower, as in Fig. 6, the depressor will be moved outwardly, and hence out of the way of the advancing card, so as to allow the latter to be still farther advanced, as in Fig. 7, 35 in which a card shifter is shown in position to nearly bring the advancing card in position within a compartment into which the card is to be shifted. It is understood that the card-shifter is advanced sufficiently to push the advancing card entirely through passage A³ and to leave the card over the follower in the compartment in which a new pack is being formed. The operation of each one of these depressors is the same, one being brought into action during 40 the forward movement of each card-shifter, so that the cards from a pack in either compartment can be successively shifted therefrom to form a pack in the opposite compartment. It will be observed that as soon as the 45 depressor moves outwardly and releases a follower under it the advancing card between the follower and the front of the box will keep the follower back as it is farther advanced, so that the depressor is only necessary for allowing the advancing cards to lap over the follower or any card or cards thereon, after which the advancing cards will successively push back the follower and cause the latter to yield to the gradually-increasing pack.
- 50 The depressors could consist of pins passing through holes in the front of the box and secured to cross bars outside of the latter; but preferably each depressor consists of a comparatively narrow plate, g, arranged to work through a slot, g', formed transversely through the front of the box or case, as in Fig. 9. Each depressor is formed with or secured to a vi-

bratory yoke, the sides or legs G' of which are pivotally supported at the sides of the box. These yoke-frames are bent so as to straddle the box, and one yoke is widened at its middle, so as to lie outside of the remaining yoke. Under such arrangement the middle portion of each yoke, which is constructed to provide a depressor, crosses the front of the box, and is then bent down at the sides of the latter to a short extent, after which the yoke runs outwardly or toward an end of the box, so as to form the legs G', which are parallel with the sides of the box and pivoted thereto. Each 80 one of these legs has a cam, G², (best shown in Fig. 3,) which said cams are formed at or near the outer ends of the legs of the yoke.

The depressors G are normally held in their forward position, as in Fig. 7, by means of 85 one or more springs, H, arranged on the front of the box or otherwise disposed so as to act upon the yoke-frames. These springs also serve to maintain the yokes in such position as to bring their cams or projections in the path 90 of projections carried by the card-shifters, so that when a card-shifter is moved forward it will engage the cams on one of the yokes and operate the yoke in order to move the depressor thereon inwardly. Said projections 95 carried by the card-shifters are conveniently formed of pins D³, projecting from the sleeves D⁴ toward the sides of the box. In this way, when a card-shifter is moved forward over one compartment, so as to advance the top card 100 from a pack in said compartment, the pair of pins D⁵, carried by said advancing card-shifter, will, during the first part of its forward movement, strike against the cams belonging to a yoke carrying that depressor which is over 105 the compartment into which the card is to be shifted. As the pins strike and ride along these cams, the said yoke will be tilted so as to throw its depressor back into the box, in order to push back or inwardly the follower under such depressor, and as long as the pins are in engagement with these cams the yoke and the depressor thereon will be maintained in such position.

Fig. 6 illustrates a yoke maintained in such 115 position as to bring the depressor against a follower and to such extent in the box as to hold the follower back in order to allow room for an advancing card. The depressor is kept in such position until the advancing card overlaps the follower, as shown in Fig. 6, after which the pins of the advancing card-shifter clear the cams and allow the springs to throw the depressor outwardly and out of the way of the advancing card, as in Fig. 7. By such arrangement a 120 depressor is operated only during a portion of the advance movement of a card-shifter, and the mechanism is so timed that the depressors shall not interrupt the forward movement of a card from either compartment.

In order to give notice to the passengers in a car that a card has been shifted, so as to call their attention to the name of the crossing to which the car is approaching, and also such 125 130

advertisement as may be placed on the card, a bell or bells will be arranged in such way that when a card is or has been shifted a bell shall be rung. As a convenient arrangement 5 of bells and means for sounding the same at the proper moments, I provide upon one of the sides of the box a pair of bells or gongs, I. Each card-shifter carries a device by which, at the proper moment during the advance of the card-shifter, the tongue or clapper for one of the bells shall be operated. For this purpose one of the sleeves D⁴ of each card-shifter carries an arm, K, provided with one or more teeth or projections. The bell-clappers L, one of which 15 is provided for each bell, each consist of an extension of a coiled spring, L', said extension being at its free end provided with a button for striking the bell. Referring more particularly to Figs. 3 and 4, each spring L' is arranged about a stud, M, secured on the box. Each of said studs has a shoulder, m, located above said spring, and upon said shoulder is arranged an oscillating plate or hub, N, provided with a stud or finger, n, normally kept 25 in the path of the teeth on an arm, K, of the nearest shifter by means of a spring, N', attached to the stud M and to the hub N. Each hub N is also provided on its under side with a pin, N², and below said hub is arranged a 30 stop, N³, secured to the box.

The arrangement and operation of these parts are as follows: The springs N' normally maintain the teeth or fingers n on the hubs in the path of the teeth on arms K, carried with 35 the card-shifters, and when the clappers are at a state of rest the stops N³ keep the striking ends of the clappers off from the bells. The tooth of an advancing arm, K, engages the finger n of the nearest oscillatory hub and turns 40 the latter so that the pin or finger N² on said hub shall act against the spring-arm of the clapper and swing the same away from the bell, thereby winding up the spring of the clapper, and also winding up the spring which controls 45 the hub. As soon as the hub is released by reason of a further advance of arm K, the hub will be instantly swung back by its spring, and hence the clapper will be free to be swung back and sound the bell by reason of the unwinding 50 action of its spring as well as by its individual spring action.

Obviously a variety of ways will suggest themselves in which a bell could be sounded at each transfer of a card from one compartment to the other, and hence I do not limit myself to the precise mechanism, since in this part of my invention the prominent feature is a bell and means by which at each transfer of a card the bell is rung or sounded.

60 The box can be made, as in Fig. 2, with its greatest length coincident with the line of travel of the cards; but in many instances, owing to the space available for the apparatus, it is preferable to make the box wider and of 65 a decreased length, as in Figs. 10, 11, and 12.

A box of these dimensions will require or can, if desired, be inclosed by a case, P, substan-

tially of the shape shown in Fig. 1, although of course the case can be made to suit a box of the form shown in some of the remaining 70 figures where a box of such character is employed. Where the box is thus inclosed in a case P, the latter will have an opening coinciding with the opening in the front of the box, and said case will also have any suitable 75 arrangement of door or hinged side or sides, so as to allow access to the box for the purpose of putting in or taking out cards from the latter. The box will also be provided with one or more doors or lids--such, for example, as 80 a sliding lid, Q, Fig. 3, which lid, however, can be hinged when found more convenient.

This apparatus is especially applicable for use in street-cars, and can be either permanently secured in the car at one end thereof 85 or can be temporarily hung up in the car and secured by buttons or the like, so that at the end of each trip the box can be moved by the conductor from one to the other end of the car.

90 A variety of means can be adapted for operating the shifters from one or both ends of the car; and while the shifters could be operated by slides, levers, or other analogous mechanisms, I have herein illustrated a cord 95 as the operating medium, since the same can be conveniently run from the apparatus through the end of the car and terminate outside the latter in a weighted button, which shall be within convenient reach of a conductor standing on either end platform of the car. The cord or cords can pass over pulleys arranged in or on the car-walls, and as soon as the car has passed one crossing a pull on the cord will operate such one of the shifters as 100 the cord may be connected with, and thereby expose a card indicating the next crossing to which the car is approaching. These operations can be repeated until the end of the trip, at which time the cards from a pack in one 105 compartment will have been transferred to and collected in pack form in the remaining compartment. On the return-trip no handling of the cards will be necessary, since by changing the connection of the cord with the shifting device the cards can in the same way as before be successively shifted back into the first compartment, in which they will collect 110 in regular order and in pack form ready for the next trip. As the order of the cards is 115 thus preserved with relation to the required successive display of the cards, it will not be necessary to open the box except for the purpose of replacing cards by others containing new advertisements, or in the first instance 120 introducing the pack.

125 A convenient way of operating the shifters where the apparatus is to be hung up in a street-car is shown in Figs. 10, 11, and 12, in which S denotes the main operating - cord, 130 which can be run either way from the box, as in full or dotted lines, Fig. 12. The cord passes over any suitable arrangement of pulley or pulleys and at one end connects with a cross-

bar, T, arranged to slide along guide-rods U, which stand out from the front of the box and are secured at their inwardly-bent ends to the latter. The sliding cross-bar T is guided on these rods by eyes *t* or the like on the bar encircling the guide-rods, one of which said eyes is shown in Fig. 12. The guide-rods should each have a stop, *t'*, located at or about the bend at its lowest end, so as to prevent the cross-bar T from slipping over said bend when the cord is slackened up. Cords W are attached to the cross-bar T, near the ends of the bar, and at their free ends each provided with a hook. These cords W pass over or around pulleys *w*, situated at or near the middle of the box, on the front thereof, and these cords are attached by their hooks to such shifter as is to be operated, for which purpose the bar D² of each shifter can be provided with a pair of eyes or staples, with which the hooks can be readily connected. Thus in Fig. 10 the cords W are shown attached to the cross-bar D² of the lower card-shifter, and hence by drawing on cord S the said shifter will be moved up or forward, and as soon as said cord is released the springs E will force the shifter to its original back position. This attachment of cords is also illustrated in dotted lines, Fig. 12.

In Figs. 11 and 12 the cords W (shown in full lines) pass around pulleys *w*, and are attached to the cross-bar D² of the upper shifter, so that by drawing on cord S this upper shifter will be operated. The pulleys *w* will each be arranged in any suitable block, strap, or yoke for preventing the cord from slipping off the pulley, in which case the block or strap can be formed in any way convenient for permitting the cord to be removed from the pulley or trained over the same, as occasion may require. Obviously, however, numerous ways can be provided for operating the shifters, and hence I do not limit myself to any special means. Thus this apparatus can be employed to advantage in a railway-car for indicating stations, in which case, in place of advertisements, distances between stations might be preferable. The apparatus could be set or hung up at one end of the car and operated by a brakeman, who could, in lieu of calling out stations, move the shifters through the medium of any suitable connection passing through a slot in the box and case. The gong or bell would in this instance call the attention of the passengers to the card thus exposed.

This apparatus could also be employed in any other connection where cards are to be used in the manner hereinbefore described—as, for example, the apparatus inclosed by an appropriate casing may be employed for displaying advertisements in hotels and other public places, in which case the cards may be alternately provided with photographs and advertisements, and the use of cords dispensed with, it being obvious that means for operating the apparatus for such purpose could be

provided without the exercise of invention—as, for example, a knob extending from the slide through a slot in the casing.

Having thus described my invention, what I claim is—

1. An apparatus for shifting and displaying cards and the like, provided with a pair of card-receiving compartments connected together by a card-passage, and two independent card-shifting slides, both in line with but respectively at opposite sides of the said card-passage, each card-shifting slide being independently operative of the other and operative over one of the two compartments, substantially as described, and for the purpose set forth. 70

2. An apparatus for shifting and displaying cards and the like, provided with a pair of card-shifting slides, each arranged over one of two card-receiving compartments, which are connected together by a card-passage arranged intermediate of the two card-shifting slides, each one of the card-receiving compartments being provided with a spring-follower arranged to maintain the top card of a pack in line with the card-passage and the card-shifting slide, substantially in the manner and for the purpose described. 85

3. The combination, with the two card-receiving compartments connected together by a card-passage and each provided with a spring-follower, of the two independent card-shifting slides D, both in line with the card-passage and each applied to reciprocate over one of the two compartments, and a depressor, operating substantially as described, for temporarily depressing the spring-follower in one card-receiving compartment during the advancement of the card-shifter over the other compartment, for the purpose set forth. 95

4. The combination, with the two card-receiving compartments connected together by a card-passage, and each provided with a spring-follower, of the card-shifting slides D, operative at opposite sides of the card-passage, depressors G, each for temporarily depressing the spring-follower in one compartment during the advancement of one of the card-shifting slides over the other compartment, and means, substantially as described, for operating the depressors by and during the forward movements of the card-shifting slides, for the purpose set forth. 110

5. The combination, with the box provided with two card-receiving compartments connected together by a card-passage and each containing a spring-follower, of the card-shifting slides D, operating substantially as described, and the depressors G, each connected with a pivoted yoke-frame and arranged to work through a slot formed transversely through the front of the box, said slots being located, respectively, at opposite sides of the card-passage, and the yokes being hung in position to be acted upon by the card-shifting slides, substantially in the manner and for the purpose described. 125

6. In an apparatus for the purposes de-

- scribed, the card-shifting slides, both arranged in one and the same plane, and each arranged to be moved over one of a pair of communicating card-holding compartments, in combination with the springs located between the card-shifters and arranged to be compressed when either card-shifter is moved forward to shift a card from one compartment to the other, substantially as described.
- 5 10. 7. The pair of card-shifting slides D, each consisting of a plate provided with corner projections, D', for the purpose described, in combination with the double card-holding box and means for operating either card-shifter independently of the other, substantially as set forth.
- 15 8. The box provided with a pair of communicating card-holding compartments, each containing a spring-follower, in combination with the pivoted yokes, each provided with a depressor, G, and one or more cams, G², for the purposes set forth, and the card-shifting slides D, each carrying a projection adapted to engage a cam of one of the yokes during a portion of the forward movement of the card-shifting slides, substantially as described.
- 20 9. In an apparatus of the character described, the card-shifting slides D, both arranged in one and the same plane and each 30 arranged to be moved forward over one of a pair of communicating card-holding compartments, in combination with one or more bells and bell-actuating devices constructed to be operated by and during the forward movement of either card-shifter, substantially as described.
- 35 10. In an apparatus for the purpose described, the communicating card-holding compartments, in combination with the card-shifting slides D, working in guideways A³, and the cross-bars D², attached to the card-shifting slides, substantially as set forth.
- 40 11. In an apparatus for the purpose set forth, the card-shifting slides D, arranged to work in a plane over two card-holding compartments 45 communicating with each other, substantially as described, in combination with springs E, supported at the sides of the apparatus, the cross-bars D², and the sleeves D⁴, fitted to slide on guide-rods on which said springs are arranged, substantially as set forth.
12. In an apparatus of the character and for the purpose set forth, the card-shifters, in combination with bells I, the spring-clappers L L', the oscillatory hubs N, the stops N² N³, and the arms carried by the card-shifters and adapted to actuate the hubs during the forward movements of the card-shifters, for the purposes described.
13. In an apparatus for the purpose described, the card-shifters, in combination with an operating-cord, a cross-bar, T, sliding on guides at the front of the apparatus, the cords W, by which said sliding cross-bar can be connected with either card-shifter, and pulleys for 60 guiding said cords, substantially as set forth.
14. The combination, with a box provided with two card-receiving compartments connected together by a single card-passage and each containing a spring-follower, of means, substantially as described, for shifting the top card from a pack of cards in either compartment through the card-passage and into the other compartments, means, substantially as described, for depressing the follower in one compartment at a time during the advancement of a card from the other compartment, and means, substantially as described, for relieving the pressure upon said follower as soon as the advancing card has advanced sufficiently to lap 70 over the follower, substantially as described.
15. In testimony whereof I have hereunto signed my name in the presence of the two subscribing witnesses.
- MARSENA M. HOOTON.
